UNITED STATES PATENT OFFICE.

WILLIAM ALBERT ROHR, OF SOREL, QUEBEC, CANADA.

AIR-COMPRESSING APPARATUS.

No. 832,812.

Specification of Letters Patent.

Patented Oct. 9, 1906.

Application filed December 11, 1903. Serial No. 184,821.

To all whom it may concern:

Be it known that I, WILLIAM ALBERT ROHR, of the town of Sorel, in the Province of Quebec and Dominion of Canada, have invented 5 certain new and useful Improvements in Air-Compressing Apparatus; and I do hereby declare that the following is a full, clear, and exact description of the same.

My invention has for its object to secure 10 the maximum compressive energy from dynamic force.

The invention may be said briefly to consist of a weight offering relatively slight resistance to movement and having a high degree 15 of compressive energy represented by dead-weight and a series of receptacles, each adapted to contain a body of fluid to be compressed, compressible means being located in the path of and adapted to be compressed by 20 said weight as it moves, while intermedial means are operated by said compressive means and adapted to compress the fluid in said receptacle.

For full comprehension, however, of my 25 invention reference must be had to the accompanying drawings, forming a part of this specification, in which similar reference characters indicate the same parts, and wherein—

Figure 1 is a plan view of the base and rails 30 of an air-compressing apparatus constructed according to my invention. Fig. 2 is a longitudinal vertical sectional view thereof, taken on line A A, Fig. 1. Fig. 3 is a transverse vertical sectional view, and Fig. 4 is a 35 side elevation of my complete apparatus.

The foundation or bed *b* for supporting my improved apparatus is preferably made of concrete, and a pair of longitudinals *c*, one located near each side edge thereof, support 40 a pair of guiding-rails *d*, preferably of triangular cross-section. These rails are supported at a sufficient height above the bed or foundation to accommodate a series of cylinders *e*, pivoted at their lower ends, as at *f*, to 45 the bed and containing pistons *h*, with piston-rods *i*, projecting through the upper ends of the cylinders and having bearing members *j*, each in the form of an arc, corresponding in radius to the main compressive member, to 50 be presently described, and such bearing members having antifriction-rollers *j* set therein. These cylinders are preferably arranged in staggered relation, and a pair of props or supports *k* are located at opposite 55 sides of each cylinder and are carried rigidly by the bed in a line extending diametrically

through the cylinders and longitudinally to the rails. An expansile spring *m* yieldingly retains each bearing member and with it the piston-rod and piston in its uppermost position.

My improved compressing member consists of a rolling weight, preferably in the form of a solid cylinder *n*, constructed of material of great specific gravity and being 65 of a length to extend completely across the space between the rails. A pair of wheels *o* are secured rigidly to the ends of this rolling weight and have their peripheries formed with angular grooves to receive the rails. 70 The perimeter of the cylinder has a series of sprocket-teeth encircling same about midway of its length, and the upper strand of an endless chain, looped at its opposite ends over driving-sprockets *p*, engages the uppermost 75 teeth in order that when these driving-sprockets are rotated the weight will be caused to roll from one end to the other of the rails and back again when the direction of rotation is reversed.

In the operation of my compressor the cylinders turn on their pivots as the roller passes over them, so as to keep the concave faces of the bearing members *j* turned toward the roller.

What I claim is as follows:

1. In an air-compressing apparatus, the combination with a base, a weighted rotary member adapted to rest upon such base, and means for rolling the said member to and fro, 90 of a cylinder, means pivotally supporting such cylinder below the surface of the said base, means for supporting the cylinder in an angular position facing the end of the base from which the member rolls, a piston movable in the cylinder, a piston-rod connected at one end to the piston, means yieldingly supporting the said piston with the opposite end of the piston-rod normally above the level of such surface and in position to be actuated upon and depressed by the weighted member, the said cylinder being adapted to oscillate in a plane parallel to the direction of travel of the rotary member and move with the said member while the latter acts upon 105 the piston-rod.

2. In an air-compressing apparatus, the combination with an air-compressing cylinder having intake and outlet ports, a piston movable in said cylinder, a piston-rod connected at one end to the piston and having its opposite end projecting outside of the cyl-

- inder, of a pair of parallel longitudinals, means pivotally supporting the lower end of said cylinder between said longitudinals to oscillate in a plane parallel to the said longitudinals, a weighted rotary member supported upon the longitudinals and extending across the space therebetween, means for rolling said member from one end to the other of the said longitudinals, the outer end of such piston-rod projecting into the path of the rotary member and the said cylinder being adapted to be moved by the rotary member as it rolls over the same, means yieldingly supporting the piston at the end of the cylinder adjacent to the rotary member, and means for supporting said cylinder in an angular position facing the end of the longitudinals from which the compressing member rolls.
3. In an air-compressing apparatus, the combination with a series of air-compressing cylinders arranged in staggered relation, each cylinder having intake and outlet ports, a series of pistons one within each cylinder, a series of piston-rods one connected to each piston and the said piston-rods having their opposite ends projecting outside of the cylinders, a series of bearing members one carried upon the outer end of each piston-rod, of a pair of longitudinals one at each side of said series of cylinders, means pivotally supporting the lower ends of said cylinders between the longitudinals to oscillate in a plane parallel to the longitudinals, a weighted rotary compressing member supported upon the longitudinals and extending across the space therebetween, said member being of solid cylindrical form, means for rolling the member from one end to the other of the longitudinals, means yieldingly supporting the piston at the end of the cylinder adjacent to the rotary member and means for supporting each cylinder in an angular position facing the end of the longitudinals from which the compressing member rolls, said compressing member being adapted when rolled to bear upon the said bearing members and move the pistons in the cylinders.
4. In an air-compressing apparatus, the combination with a series of air-compressing cylinders arranged in staggered relation, each cylinder having intake and outlet ports, a series of pistons one within each cylinder, a series of piston-rods one connected to each piston and the said piston-rods having their opposite ends projecting outside of the cylinders, a series of bearing members one carried upon the outer end of each piston-rod, of a pair of longitudinals one at each side of said series of cylinders, means pivotally supporting the lower ends of said cylinders between the longitudinals to oscillate in a plane parallel to the longitudinals, a weighted rotary compressing member supported upon the said longitudinals and extending across the

space therebetween, said member being of solid cylindrical form, means for rolling the member to and fro between the ends of said longitudinals, means yieldingly supporting the piston at the end of the cylinder adjacent to the rotary member and means for supporting the cylinders in angular positions facing the end of the longitudinals from which the member rolls, said member being adapted when rolled to bear upon the said bearing members and move the pistons in the cylinders and simultaneously oscillate said cylinders.

5. In an air-compressing apparatus, the combination with a series of air-compressing cylinders arranged in staggered relation, each cylinder having intake and outlet ports, a series of pistons one within each cylinder, a series of piston-rods connected to the respective pistons and each having one end projecting outside of its cylinder, and a series of bearing members carried upon the outer ends of the respective piston-rods, of a pair of longitudinals one at each side of said series of cylinders, means pivotally supporting the lower ends of said cylinders between said longitudinals to oscillate in a plane parallel to the longitudinals, a weighted rotary compressing member supported upon the said longitudinals and extending across the space therebetween, said member being of solid cylindrical form between the ends of the longitudinals, means for supporting the cylinders in angular positions facing the ends of the longitudinals, said compressing member being adapted when rolled to bear upon the said bearing members and move the pistons in the cylinders and simultaneously oscillate said cylinders, means yieldingly supporting the piston at the end of the cylinder adjacent to the rotary member, and means for rolling the compressing member consisting of a series of sprocket-teeth encircling said member midway of its length a sprocket-chain in operative connection with said teeth and means for reciprocating said chain, substantially as described and for the purpose set forth.

6. In an air-compressing apparatus, the combination with an air-compressing cylinder having intake and outlet ports, a piston movable in said cylinder, a piston-rod connected at one end to the piston and having its opposite end projecting outside of the cylinder, and a bearing member carried upon the outer end of such piston-rod, of a pair of longitudinals located one at each side of said cylinder, means pivotally connecting the lower end of said cylinder between said longitudinals and to oscillate in a plane parallel thereto, a weighted rotary member supported upon said longitudinals and extending across the space therebetween, means for rolling said member from one end to the other of said longitudinals, and means for supporting said cylinder in an angular posi-

tion facing the end of the longitudinals from which the compressing member rolls.

7. An air-compressing apparatus, the combination with a series of air-compressing cylinders arranged in staggered relation, each cylinder having intake and outlet ports, a movable piston, a piston-rod connected at one end to the piston in each cylinder and having its opposite end projecting outside of the cylinder, and a bearing member carried upon the outer end of each piston-rod, of a pair of longitudinals one at each side of said series of cylinders, means pivotally connecting the lower ends of said cylinders between said longitudinals to oscillate in a plane parallel thereto, a weighted rotary compressing member supported upon the said longitudinals and extending across the space therebetween, said member being of solid cylindrical form, means for rolling said member from one end to the other of said longitudinals, and means for supporting said cylinders in an angular position facing the end of the longitudinals from which the compressing member rolls, said compressing member being adapted when rolled to bear upon the said bearing members and move the pistons in the cylinders.

8. An air-compressing apparatus, the combination with a series of air-compressing cylinders arranged in staggered relation, each cylinder having intake and outlet ports, a movable piston, a piston-rod connected at one end to the piston in each cylinder and having its opposite end projecting outside of the cylinder, and a bearing member carried upon the outer end of each piston-rod, of a pair of longitudinals one at each side of said series of cylinders, means pivotally connecting the lower end of said cylinders between said longitudinals to oscillate in a plane parallel thereto, a weighted rotary compressing member supported upon the said longitudinals and extending across the space therebetween, said member being of solid cylindrical form, means for rolling said member back and forth between the ends of said longitudinals and means for supporting said cylinders in angular positions facing the ends of the longitudinals, said compressing member being adapted when rolled to bear upon the said bearing members and move the pistons in the cylinders and simultaneously oscillate said cylinders from one angular position to the other, a series of sprocket-teeth encircling said member midway of its length, a sprocket-chain in operative connection with said teeth and means for reciprocating said chain, substantially as described and for the purpose set forth.

55 50 longitudinals, said compressing member being adapted when rolled to bear upon the said bearing members and move the pistons in the cylinders, and simultaneously oscillate said cylinders from one angular position to the other.

9. In an air-compressing apparatus, the combination with a series of air-compressing cylinders arranged in staggered relation, each cylinder having intake and outlet ports, a movable piston within each cylinder, a piston-rod connected at one end to the piston in each cylinder and having its opposite end projecting outside of the cylinder, and a bearing member carried upon the outer end of each piston-rod, of a pair of longitudinals one at each side of said series of cylinders, means pivotally connecting the lower ends of said cylinders between said longitudinals to oscillate in a plane parallel thereto, a weighted rotary compressing member supported upon the said longitudinals and extending across the space therebetween.

10. An air-compressing apparatus, the combination with a series of air-compressing cylinders arranged in staggered relation, each cylinder having intake and outlet ports, a movable piston, a piston-rod connected at one end to the piston in each cylinder and having its opposite end projecting outside of the cylinder, and a bearing member carried upon the outer end of each piston-rod, of a pair of longitudinals one at each side of said series of cylinders, means pivotally connecting the lower end of said cylinders between said longitudinals to oscillate in a plane parallel thereto, a weighted rotary compressing member supported upon the said longitudinals and extending across the space therebetween, said member being of solid cylindrical form, said member being adapted to be rolled back and forth between the ends of said longitudinals and means for supporting said cylinders in angular positions facing the ends of the longitudinals, said compressing member being adapted when rolled to bear upon the said bearing members and move the pistons in the cylinders and simultaneously oscillate said cylinders from one angular position to the other, a series of sprocket-teeth encircling said member midway of its length, a sprocket-chain in operative connection with said teeth and means for reciprocating said chain, substantially as described and for the purpose set forth.

In testimony whereof I have affixed my signature in presence of two witnesses.

WILLIAM ALBERT ROHR.
